SHOE SOLE

Arthur Fisch, Heidelberg, Germany

Application May 5, 1938, Serial No. 206,244
In Germany January 8, 1938

8 Claims. (Cl. 36—29)

The invention relates to footwear and has for an object to provide improvements therein which render the footwear particularly comfortable.

Normal boots and shoes incorporate rigid supporting means to support the arches of the foot, which, however, often break through after a short wearing or lose their form in some way, so that they are no longer a help but rather the cause of much discomfort.

10 The natural rolling of the foot from the heel to the tip can only be ensured by a sole which bears correctly against the foot and gives complete liberty of movement to the foot. Thereby the sinews and the ligaments of the foot and leg bones which 15 carry out their natural functions are reinforced and remain elastic and are then capable of their maximum effort. To come as near as possible to this ideal state is the aim of the invention. Particularly, the invention seeks to provide improvements in house shoes which usually do not 20 allow rigid supports and heels, as for example in cosy shoes and slippers, due to the nature of the material from which they are manufactured; hitherto it has been tried to overcome these inconveniences by omitting the heels and supports 25 for the ankles, which have been found extremely disadvantageous for the wearer.

The invention overcomes these defects by the arrangements described below.

30 A sole carried out in accordance with the invention, from rubber or similar material, is represented in the accompanying diagrammatic drawing by way of example, in which:

Figure 1 shows the rubber sole in section on the line I—I of Figure 2.

Figure 2 is a view of the rubber sole in top plan with the upper covering removed.

Figure 3 shows the sole in section on the line III—III of Figures 1 and 2 after the upper has 40 been attached.

Figure 4 shows the sewing-on edge with an upper sewn on in the initial position to the sole.

Figure 5 shows the sewing edge after the turning of the upper.

45 In accordance with the invention the sole consists in the following parts: The heel *a*, the arch support *b*, the metatarsal arch support *c* and the toe part *d*. The heel *a* is composed elastically of hollow cells *1*, and is comfortable to the foot.

50 The arch support *b* has at its under side a number of integral studs or projections *2*, and on its upper side comprises arch supporting ribs *3*, which are formed resiliently, being integral ribs of rubber. The metatarsal arch support *c* which conforms to the natural arch of the foot

is also, as can be seen at *4*, elastically sub-divided by webs. The studs or projections *2* bear on the ground during walking and assist in lengthening the life of the sole. As the studs are separate from one another, they in no way prevent the sole from flexing as required by the act of walking. The toe of the sole is also made more resilient by web forming cells *5*, whilst between this part and the commencement of the arch support *c* the sole is formed at its inner surface with 10 transverse corrugations *6*. These corrugations *6*, as shown in Figure 2, also extend along one side of the sole to where the heel part *a* commences leaving the webs *3* and *4* for supporting the longitudinal and metatarsal arches of the 15 foot, which latter is shown in Figure 3. The sole is provided at its upper surface with a resilient covering or insertion *12*, which by virtue of the formation above described, assumes a shape natural to the foot and enables it to obtain a 20 proper grip during walking.

The stable heel *a* brings the foot in its normal position and results, in connection with the external support *2*, the longitudinal arch support *3*, the metatarsal arch support *4* and the elastic 25 bearing *5* of the toe part—contrary to the hitherto known form and manner of manufacture of cosy shoes and slippers—in a favourable mounting of the foot in all respects whereby the above mentioned defects are eliminated. 30

The arrangements in accordance with the invention are also applicable advantageously in other types of manufacture, for example in shoes which are sewn throughout and in which the upper worked with its margin turned outwardly 35 while on a last so that a flange is created to which the tread sole is then sewed, and also in shoes provided with unvulcanized soles. The inner surface of the rubber sole which faces the foot, with the exception of the sewing-on margin *1*, is provided with hollow spaces, in order to give to the 40 foot a soft smooth resting to favour the airing and to reduce the weight.

The making of shoes with heel and arch supports cannot generally be carried out in accordance with the known method of sewing on the sole portion to the upper portion without the employment of complicated and expensive machinery. In the present invention, the attachment of the outer sole, which is provided with 45 heel and arch supports, is effected with parts outturned and the upper inside out and the shoe is turned right side out after sewing which enables the sewing on of the upper of the shoe to be accomplished with the simplest sewing 50 55

machine. This is accomplished by placing the sole upon the sewing machine with its foot-contacting surface facing upward (Figure 4). The laterally extending sewing-on margin rests then entirely flat upon the sewing table. Afterwards the upper of the shoe is while turned inside out connected with the sewing-on edge, the juxtaposition of the sewing-on edge and the upper is such that only the sewing-on edge and upper 10 come in contact with the pressing foot and the feeder of the machine. The raised parts, such as heels, arch supports etc. do not come in contact at all with the sewing device itself. Then the upper is turned inside out. (See Fig. 5.)

15 Hitherto, because of the sewing methods used, heavy weight materials have been necessary. In the arrangement of the present invention, however, any weight material may be employed in view of the position of the sewing-on margin with 20 respect to the machine.

25 A special advantage of the carrying out of the seaming edge in accordance with the present invention consists in the fact that the upper of the boot here can be fastened by the simplest stitching operation.

Moreover, this sole prevents the bulge at the bottom of the shoe seen in the usual turn-shoe work which leads to foot troubles. Furthermore, this sole prevents the flat resting of the foot, 30 leading to flat feet, which ordinarily results from the lack of a heel. Usually when there is no heel, the weight is thrown backwards when the foot is at rest. The disadvantages brought about by the shifting of the weight are not removed by 35 the mere insertion of a wedge underneath the heel. For although the wedge lessens some of the shifting of weight, it nevertheless permits the longitudinal arch of the foot to swing freely without any support, so that the arch falls.

40 All these disadvantages are overcome by the sole formed in accordance with the present invention.

I claim:

1. For footwear a combined sole and heel 45 formed from rubber and comprising a heel portion, a shank portion and a sole portion, upwardly directed ribs formed on the heel portion and the shank portion to provide an air cushion thereover, a plurality of downwardly directed studs formed integrally upon the shank portion 50 and arranged with their extremities disposed substantially in co-planar relationship to the under surface of the sole and the heel portions, and a metatarsal arch support conforming to the 55 natural arch of the foot and being sub-divided by webs extending from the arch support to the sole.

2. For footwear a combined sole and heel 60 formed from rubber and comprising a heel portion, a shank portion and a sole portion, upwardly directed ribs formed on the heel portion and the shank portion to provide an air cushion thereover, and a plurality of downwardly directed studs formed integrally upon the shank portion 65 and arranged with their extremities disposed substantially in co-planar relationship to the under surface of the sole and the heel portions, the toe portion of the sole having upwardly directed ribs formed integrally thereon to constitute an air-cushion, said ribs being graduated in height from a maximum at the end portion rearwardly, whereby the toe of the wearer is resiliently supported in an elevated position.

3. For footwear a combined sole and heel 75 formed from rubber and comprising a heel por-

tion, a shank portion and a sole portion, upwardly directed ribs formed on the heel portion and the shank portion to provide an air cushion thereover, and a plurality of downwardly directed studs formed integrally upon the shank portion 5 and arranged with their extremities disposed substantially in co-planar relationship to the under surface of the sole and the heel portions, the inner surface of the sole provided with transverse corrugations extending along one side of the sole 10 to where the heel part commences.

4. For footwear a combined sole and heel formed from rubber and comprising a heel portion, a shank portion and a sole portion, the lower surface of which latter is substantially flat, 15 upwardly directed ribs formed on the front of the sole portion to provide an air cushion serving to elevate the wearer's toes, a plurality of downwardly directed studs formed integrally upon the shank portion and arranged with their extremities disposed substantially in the same plane as the lower surface of the flat sole portion, and a metatarsal arch support conforming to the natural arch of the foot and being sub-divided by webs extending from the arch support to the 25 sole.

5. For footwear a combined sole and heel formed from rubber and comprising a heel portion, a shank portion and a sole portion, the lower surface of which latter is substantially flat, 30 upwardly directed ribs formed on the front of the sole portion to provide an air cushion serving to elevate the wearer's toes, and a plurality of downwardly directed studs formed integrally upon the shank portion and arranged with their extremities disposed substantially in the same plane as the lower surface of the flat sole portion, 35 the inner surface of the sole provided with transverse corrugations extending along one side of the sole to where the heel part commences.

6. For footwear a combined sole and heel formed from rubber and comprising a heel portion, a shank portion and a sole portion, the lower surface of which latter is substantially flat, 40 upwardly directed ribs formed on the front of the sole portion to provide an air cushion serving to elevate the wearer's toes, a plurality of downwardly directed studs formed integrally upon the shank portion and arranged with their extremities disposed substantially in the same plane as the lower surface of the flat sole portion, 45 a longitudinal arch support and a metatarsal arch support conforming to the natural arch of the foot and being sub-divided by webs forming cells and extending from the metatarsal arch 50 support to where the heel commences.

7. For footwear a combined sole and heel formed from rubber and comprising a heel portion, a shank portion and a sole portion, the lower surface of which latter is substantially flat, 60 upwardly directed ribs formed on the front of the sole portion to provide an air cushion serving to elevate the wearer's toes, and a plurality of downwardly directed studs formed integrally upon the shank portion and arranged with their extremities disposed substantially in the same plane as the lower surface of the flat sole portion, 65 the inner surface of the sole provided with transverse corrugations extending along one side of the sole to where the heel part commences, the heel part and the shank portion having resilient webs consisting of cells.

8. For footwear a combined sole and heel formed from rubber and comprising a heel portion, a shank portion and a sole portion, the 75

lower surface of which latter is substantially flat, upwardly directed ribs formed on the toe portion of the sole, said ribs being graduated in height from a maximum at the end portion rearwardly to resiliently support the wearer's toes in an elevated position, and a plurality of downwardly

directed studs formed integrally upon the arch support and arranged with their extremities disposed substantially in the same plane as the lower surface of the flat sole portion.

ARTHUR FISCH.
